UNITED STATES PATENT OFFICE.

KENNETH HOWIE, OF NORRISTOWN, PENNSYLVANIA, ASSIGNOR TO WILDMAN MFG. CO., OF NORRISTOWN, PENNSYLVANIA, A CORPORATION OF PENNSYLVANIA.

METHOD, APPARATUS, AND PRODUCT OF KNITTING.

Application filed March 9, 1923. Serial No. 624,010.

Measuring the length of knitted stockings by the number of courses in the web, is common practice, but, due to variations in the tension of the yarns, the stitch lengths vary 5 to such an extent that it is necessary to match the units in order to get pairs the members of which are of substantially equal length.

In the making of knit stockings, it is common practice to knit one part of the leg with one yarn and another part with another yarn, the tension of each varying more or less and producing stitches of varying length, and each yarn at times being under a tension different from that of the other yarn. It is, furthermore, common practice, to vary the length of the stitch at different points in the length of the leg, for instance, tighter stitches being formed at the region of the 20 ankle than at the region of the upper part of the leg.

An object of my invention is to produce stockings in succession from the same machine, of equal length and of the same number of courses, and also to derive these equal length stockings under the conditions above referred to of changing the yarn and varying the length of the stitch at different parts of the leg.

The machine with which the yarn furnishing mechanism herein disclosed is combined, may be of any well-known type which measures the length of the units by courses, the result of this combination being units of 35 equal length and of the same number of courses.

The invention, however, is not limited in all its aspects to the method or machine in which measuring is done by courses.

The invention resides in the method, the apparatus, and in the article produced.

In the accompanying drawings:—

Figure 1 is a side view of the yarn furnishing mechanism associated with a stocking knitting machine of the Pigeon type, though it will be understood that I do not limit myself to any particular machine in carrying out the invention.

Fig. 2 is a front view of the mechanism.

Fig. 3 is a front view of a portion of 50 Fig. 2.

Fig. 4 is a plan view showing a portion of the yarn feed mechanism of a knitting machine with which the yarn furnishing mechanism is combined. 55

Fig. 5 is a plan view of a detail.

Fig. 6 is a detail plan view of operating connections.

Figs. 7 and 8 are plan views in the nature of diagrams, showing how the self aligning 60 member of the yarn furnishing rolls may assume different positions relative to the driving cone or roll.

Fig. 9 is a sectional view of one of the 65 yarn furnishing rollers and means for driving the same.

Fig. 10 is a sectional view of the other roller which is frictionally driven from the roll shown in Fig. 9.

In carrying out the invention the yarns 70 are changed as in ordinary practice by throwing one yarn guide finger into feeding position and the other yarn feed finger is then thrown out of feeding position to carry its yarn out of work, and each yarn 75 in my invention when thrown into work, is automatically furnished to the needles by rolls in accordance with the demands thereof, irrespective of variations in tension of the yarn as it comes off from the bobbin and as it passes to the needles so that stitches of substantially uniform length will be formed.

Conversely when a yarn is thrown out of work at the needles, it is also automatically thrown out of connection with the yarn 80 furnishing means, so that all furnishing action thereon will cease, and this condition will continue until this yarn is again introduced to the needles, whereupon the yarn furnishing action will be resumed automatically. 85

The apparatus comprises, in the particular form chosen as an example of a physical embodiment of the invention, a pair of conical rollers, one of which, 1, is positively driven in unison with the knitting head, and the other of which, 2, is driven by frictional contact with the positively driven conical roll. 95

The conical roll 2 is mounted to be spring pressed against the positively driven cone, and in a manner which will permit said roll 2 to automatically accommodate itself to the conditions arising from the automatic alteration in the position of the yarn passing between them, which is constantly changing its position along the rolls, according to variations in the tension of the 10 yarn running from the bobbin to the needles, this change being due to the automatic shifting of the yarn guide along the rolls as tension changes. For this purpose the roll 2 turns on a rod 3 mounted in a bracket 4, which is pivoted at 5 to a substantially horizontal plate 6 which is pivoted at its ends 7, 8, in ears 9 of a fixed bracket 10, secured at 11 to the post or standard 12. The horizontal plate is pressed upwardly by 20 a spring 14 in a pocket 15 of the bracket 10, the spring pressure being exerted against the extension 6' of the plate 6, the effect being to press the roll 2 yieldingly against the roll 1, but permitting the said roll 2 to assume different angular positions in respect to the roll 1 in accordance with the various positions that the yarn will assume along the bite of the rollers. To illustrate, supposing the yarn to be passing through 30 the rollers at point X in Fig. 7; the roll 2 will bear on the roll 1 at its larger diameter portion, while it will be out of contact with the roll at the smaller diameter portion, due to the interposed yarn, but if 35 the yarn assumes, say a position at about X', Fig. 8, then the roll 2 will tilt the other way, always, however, under the yielding pressure of the spring, and it will be driven by its frictional contact with the larger cone 40 at its smaller diameter portion. In other words, the roll 2 is not held in rigid relation to the roll 1, but is spring pressed and will accommodate itself lengthwise to the shifting of the yarn to various positions 45 along the meeting line of the rolls, but at all times it will exert substantially uniform pressure upon the yarn.

The conical roller 1 is driven in unison with the knitting head, and in the example 50 illustrated it is driven by bevel gears 17 from a vertical shaft 18 which is driven through a gear on the lower end thereof, an intermediate gear and the gear on the knitting head of the type of machine known as the Pigeon, though, of course, the invention 55 is not limited in its use to any particular type of machine.

The yarn guides are shown at *a*, *b*. One of these is, for instance, for the yarn which 60 knits the top of the stocking leg, and the other *b* is for the yarn used for knitting the leg. There may be more than two yarns, but in either case, they are supplied to the needles by the furnishing means. These 65 yarn guides are carried by discs or members 19, mounted to have oscillating movement upon bearings carried by a bracket 20, which is secured at 21 to the tubular standard 22, which is supported at 23 in the bracket 10. These discs carry sweep arms *a*¹, *b*¹, having guides for the yarns. The bracket 20 has arms 25 with fixed guide eyes 26 for the yarns, and it has a guide-way 27 for lifter members 28. These lifters have hooks or projections 29 which engage under pins 30 on the inner sides of the discs. These pins are extensions of the screws 31^x which secure the sweep arms *a*¹, *b*¹ to the discs, and these screws are clamped by nuts 32. The lifters 28 have stems 28^a extending down through the hollow standard 22 and at their lower ends 70 they have projections 29^a to be engaged by lifting levers 31, 31^a. One of these, 31, is on a hollow shaft 32^a having an arm 33 to which is pivotally connected a hook 34 which engages the tail extension 35 of one of the arms or levers 36, 36^a which are usually employed in the Pigeon machine for controlling the position in or out of work, 80 of the yarn feed fingers which direct the yarn to the needle. The other lifting lever 31^a is on a shaft 37 which passes through the hollow shaft 32^a and carries an arm 38 to which a hook 39 is pivotally connected, which hook engages a pin on the tail extension of the lever or arm 36^a, which like the arm 36, controls the position in or out of another one of the yarn feed fingers. One of these yarn feed fingers is shown at 41, 90 down in yarn feeding position, this being due to the fact that its controlling arm 36 has been lowered, and that its spring 42 has forced it down, and the other yarn feeding finger 41^a is shown up out of service 100 due to the fact that its controlling lever is in its elevated position. The position of the controlling arms is controlled by a drum 43 having high and low parts, as usual in the Pigeon machine, which drum operates upon the arms 40 and 40^a of the levers respectively, the drum being turned by the pattern mechanism of the machine in the usual manner, and presenting its high and low parts 110 to the said arms 40 and 40^a.

The hooks 34 and 39 are pressed by springs 43 to hold them in engagement with the pins of the controller levers 36 and 36^a. 115

It will now be understood that if either of the yarn fingers 41, 41^a is operated in or out of feeding position, the corresponding yarn guide *a*, *b* will be operated in or out of active position, that is to say, when the yarn guide finger 41 of the knitting head is down in position, as shown in Fig. 1 to feed the needles, the guide *a* will be in the position 120 shown to direct the yarn between the furnishing members or rolls, which will therefore, furnish the yarn as demanded by the needles, and to compensate for the variations in the tension of the yarn, and when 130

one of these yarn feed fingers is lifted out of working position, as shown at 41^a, the corresponding yarn guide, as *b*, will be moved to inactive position, as shown in the drawings, where it will have removed the yarn controlled by it from between the conical furnishing wheels so that no yarn will be furnished to this yarn finger so long as it remains in inactive position. Thus, when a 10 yarn feed finger, as 41^a, is raised by its controlling lever 36^a, the hook 39 connected thereto will be pushed down, turning arm 38 and rock shaft 37, and raising arm 31^a so that the corresponding lifter 28 will be 15 raised, which acting on the pin 30 of the right hand disc 19, will turn this backward and throw its guide *b* to the front to inactive position as shown, to thereby remove the 20 yarn guided by it from between the yarn furnishing rolls.

The yarn guide eye *a* will be in position to direct its yarn between the conical rolls because the dropping of arm 36 to lower yarn guide finger 41 to active position, will pull 25 up on hook 34, lower lever arm 31 allowing lifter 28 at the left to drop, and permitting left-hand disc 19 to turn forward under the impulse of a spring 44 bearing upwardly on a pin 45 set in the inner face of the left hand disc. This spring gives the disc and its yarn 30 guide eye *a* their initial movement to throw the yarn passing through the eye *a* into the bite of the rolls and thereafter the disc can 35 oscillate freely in response to the variations in tension of the yarn passing through the eye of the sweep connected therewith. The drawing, Fig. 1, illustrates the condition after this spring has exerted its force on the pin 45 of the left hand disc and has been 40 pressed down again by the turning backward of the right hand disc consequent upon the lifter 28 of that disc rising and causing the pin 45^a of said right hand disc to act on the spring. The spring 44 is supported by a 45 block 44^a fixed to standard 22. The conical rolls 1, 2 have their ends sharply tapered to act as guiding surfaces for the yarns when they are being introduced between the rolls.

Considering the action of the parts shown 50 in Fig. 1, if the position of the two lifters 28 is reversed, then the spring 44 will give to the disc of sweep *b* its initial impulse to insert its yarn passing through eye *b* into position in between the rolls; thereafter the 55 draft of the yarn will hold the sweep *b* in position so that the yarn belonging thereto will be furnished to the needles by the feeding action of the rolls thereon.

The course of the yarns may be followed 60 thus:

The active yarn *x* comes from the bobbin through the left hand guide by 26, Figs. 2 and 3, thence through eye of shiftable guide *a* between the rolls, through eye of yielding 65 sweep 46, thence upwardly and through eye

of sweep *a*¹, thence to rear eye 41^b of yarn guide finger 41^a then through the front eye of said finger and to the needles.

The other, or inactive yarn *y*, passes through the right hand guide eye 26, Figs. 70 2 and 3, then through shiftable guide *b* now in inactive position to eye of the other yielding sweep 46^a, thence up through eye of sweep *b*¹ to rear eye 41^c of yarn finger 41 to the front eye thereof, and thence to the 75 needles. The yielding sweeps 46, 46^a are for the purpose of supplying yarn during the time that the shiftable guide *a* or *b* is finding its proper position along the meeting line 80 of the conical rolls. When the yarn is first introduced between the rolls, it will be furnished at first by the action of the small diameter portions of the rolls thereon, and as this may not furnish sufficient yarn at the outset, the needed supply will be drawn from 85 that portion which forms a loop extending from the rolls down through the eye of the yielding sweep 46 or 46^a and up through the sweep *a*¹ or *b*¹, as the case may be, the said yielding sweep 46 or 46^a rising during this 90 action and supplying 5 or 6 inches of yarn. The pull of the yarn being used up at the needles will almost immediately, however, result in drawing the sweep *a*¹ or *b*¹ down 95 and shifting the yarn guide arm *a* or *b* to its proper point along the rolls.

The sweeps 46 and 46^a are pivotally mounted at 47 and each is under pressure of a spring shown at 48, 48^a. The discs 19 are 100 hollow and contain quicksilver which passes from one compartment to the other thereof through an opening by which the action of said discs is damped to prevent undue vibration, as in application for Letters Patent 105 of the United States, No. 553,461, filed April 17, 1922.

Adjustable weights 49 are mounted on the discs. These will serve to turn the discs to 110 throw the yarns from between the rolls in case the yarn fails at any point between the rolls and the needles, and thus the furnishing of the yarn by the rolls will immediately cease. This will prevent the yarn from piling up under the rolls, which it would do if 115 it is not being consumed at the needles and is still passing through the rolls.

The spring 44 is common to both discs 19, operating thereon through the pins 45, 45^a thereof.

It will be seen from Fig. 1 that the pin 45 of the active disc 19, and its yarn guide *a*, is free from the spring 44, which is now held pressed down by the pin 45^a, and therefore, the yarn guide *a* can have a considerable 120 range of free oscillating movement. This spring overcomes quickly the inertia of the disc which is to become active. The weight 49 has a tendency to turn the disc and throw its yarn guide out of active position, i. e., to a position where the yarn guided thereby 125 130

will not be between the rolls and the inertia of this weight is immediately overcome by the spring when the lifter 28 falls to release the disc.

- 5 The hooks 34, 39 enable the operator to detach the yarn furnishing connections from the levers 36, 36^a so that the finger assembly and yarn clamping device can be thrown up out of action.
- 10 With the yarn furnishing means disclosed herein, the yarn is supplied to the needles at little or no tension. The usual practice is to run under considerable tension, resulting in accentuating imperfections of the fabric.
- 15 The mechanism takes care of the furnishing of each yarn and responds at once to the changing of the yarns and it in no way interferes with the adjustment of the machine for different lengths of stitches. If, for instance, the machine is automatically adjusted to make shorter stitches, the yarn guide *a* or *b* will be automatically adjusted towards the small ends of the conical rolls and will oscillate back and forth within a certain range
- 25 of an approximate position for preserving this shorter length of stitch, whereas if the machine is adjusted to make a longer stitch, the yarn guide *a* or *b* will automatically and immediately assume an approximate position nearer to the larger ends of the conical rolls and will oscillate in respect thereto to compensate for variations in the tension of the yarn and to maintain uniform the longer stitch length.
- 30 The invention is not limited to the use of plain conical rolls, but these are preferred.

It will be understood that the idle yarn end is held by a clamp within the needle circle after it is severed by a cutter also located within the needle circle, this being usual practice as for instance in the Pigeon type of stocking knitting machine.

What I claim is:—

1. In combination with a knitting machine having automatic yarn changing means, means for furnishing the yarns, comprising rotary members between which the yarns pass to be drawn thereby from the supply, shiftable yarn guides for directing the yarns between the rotary members at different points along the same to be drawn off from the supply at different rates of speed, means controlled by the variation in the tension of the yarn for shifting the yarn guides of the yarn furnishing means, and means including connections between the automatic yarn changers of the knitting machine and the yarn guides of the yarn furnishing members for automatically inserting the substitute
- 50 yarn between the rotary members and for automatically withdrawing the yarn, which has been feeding, from between said rotary members.

2. In combination with a knitting machine having yarn guide fingers with means for

automatically moving one to introduce its yarn to the needles and for moving the other to withdraw its yarn from the needles, a pair of rotary members adapted to withdraw the yarns from their supplies at different rates of speed according to the variation in tension of the yarns, and means for automatically introducing the yarns into and withdrawing them from, position between said pair of rotary members in accordance with their introduction to and withdrawal from the needles, said pair of rolls serving for both yarns, substantially as described.

3. In combination in yarn furnishing means for knitting machines, rotary members for drawing off the yarns from the supplies at different rates of speed, yarn guides shiftable along the rotary members to change the position of the yarns along said rotary members, sweeps connected with the yarn guides for shifting them according to the variations in tension of the yarns passing through and acting upon said sweeps, one of said yarns being acted on by said rotary members while the other is idle or out of effective engagement with said rotary members, and means for automatically introducing the previously idle yarn into the bite of said rotary members to become active and for withdrawing the previously working yarn from between said rotary members to idle position, substantially as described.

4. In combination, a pair of rotary members for furnishing yarn to the needles of a knitting machine, means for automatically introducing a yarn to, and withdrawing the same from, the bite of said rotary members, and a yielding yarn guide between the said rotary members and the needles to supply said newly introduced yarn to the needles while said yarn is finding its proper position along the said rotary members, and means for shifting the yarn along the rotary members to be measured off at different rates of speed according to the tension of the yarn, said last mentioned means engaging the yarn between the rotary members and the needles, substantially as described.

5. In combination, a pair of rotary members adapted to furnish yarn to the needles at different rates according to the tension of the yarn, an automatically shiftable yarn finger for introducing yarn to, or withdrawing it from, the needles, a shiftable yarn guide for shifting the yarn to different points along the said rotary members, and a connection between the said guides by which the movement of the former to and from feeding position relative to the needles will change the position of the latter to introduce the yarn to, or withdraw it from, said rotary members, substantially as described.

6. In combination, a pair of rotary members adapted to furnish yarn to the needles at different rates according to the tension of the yarn, a shiftable yarn finger for introducing yarn to, or withdrawing it from, the needles, a shiftable yarn guide for shifting the yarn to different points along the said rotary members according to its tension, and a connection between the said yarn finger 5 and said yarn guides by which the movement of the former to and from feeding position relative to the needles will change the position of the latter to introduce the yarn to, or withdraw it from, said rotary members, 10 said connection including an oscillatory carrier for the yarn guide of the rotary members and a lifter for turning said carrier to shift its guide to idle position in respect to said rotary members, substantially 15 as described.
7. In combination, a movable yarn feed finger to introduce the yarn to or withdraw it from the needles, yarn furnishing rotary members adapted to furnish yarn at different 20 rates of speed, a shiftable yarn guide to position the yarn at different points along said rotary members, an oscillating carrier for said guide, a yarn guide also connected with said carrier to turn the same according to 25 variations in the tension of the yarn, a lifter for turning the carrier to shift the yarn guide first mentioned to a position to withdraw the yarn from between the said rotary members, a connection between said lifter 30 and the said yarn feed finger of the knitting machine to shift said carrier with its yarn guide to idle position when the yarn finger is moved to withdraw its yarn from the needles, and a spring for turning the oscillatory carrier to introduce the yarn between 35 said rotary members when the yarn finger is moved to introduce said yarn to the needles, substantially as described.
8. In combination, a movable yarn feed finger to introduce the yarn to or withdraw it from the needles, yarn furnishing rotary members adapted to furnish yarn at different 40 rates of speed, a shiftable yarn guide to position the yarn at different points along said rotary members, an oscillating carrier for said guide, a yarn guide also connected with said carrier to turn the same according to 45 variations in the tension of the yarn, a lifter for turning the carrier to shift the yarn guide first mentioned to a position to withdraw the yarn from between the said rotary members, a connection between said lifter and the said yarn feed finger of the knitting machine to shift said carrier with its yarn guide to idle position when the yarn finger is moved to withdraw its yarn from the needles, and a spring for turning the oscillatory carrier to introduce the yarn between 50 said rotary members when the yarn finger is moved to introduce said yarn to 55 the needles, and an adjustable weight to move the carrier to withdraw its yarn from the rotary members when said yarn fails, substantially as described.
9. In combination, rotary members for furnishing yarn to a knitting machine, a shiftable yarn guide for positioning the yarn at different points along said rotary members to be measured off at different 60 rates, means carried by the said carrier in contact with the yarn for turning said carrier one way in accordance with changes in tension, and to thereby shift the yarn guide along said rotary members, said oscillating carrier being biased to move the yarn from between said rotary members to idle position if the yarn fails in passing to the needles, a lifter for turning the carrier to withdraw the yarn from between the rotary members, a yarn feed finger at the needles 65 connected with said lifter to operate the same when said finger is moved to idle position to withdraw the yarn from the needles, and a spring for turning the oscillatory carrier to introduce the yarn to the rotary members when said yarn feed finger is shifted to position to feed the needles and the lifter has dropped, substantially as described.
10. In combination, rotary members for furnishing yarn to the needles of a knitting machine, a pair of oscillatory carriers, a yarn guide on each carrier to direct yarn to the rotary members at different points along the same to be measured off thereby at different 70 rates, means on the carriers engaged by the yarn for changing the position of the carriers and yarn guides according to variations in the tension of the yarns, means for turning either of the carriers to and holding it in, idle position with the yarn 75 guide carrier thereby to withdraw its yarn from between the rotary members leaving the other carrier free to oscillate, and spring means for turning the carriers when released by said holding means, to introduce 80 its yarn to the rotary members, substantially as described.
11. In combination, rotary members for furnishing yarn to the needles of a knitting machine, a pair of oscillatory carriers, a yarn guide on each carrier to direct yarn to the rotary members at different points along the same to be measured off thereby at different 85 rates, means on the carriers engaged by the yarn for changing the position of the carriers and yarn guides according to variations in the tension of the yarns, means for turning either of the carriers to and holding it in, idle position with the yarn 90 guide carrier thereby to withdraw its yarn from between the rotary members leaving the other carrier free to oscillate, and spring means for turning the carriers when released by said holding means, to introduce 95 its yarn to the rotary members, substantially as described.
12. In combination, rotary members for furnishing yarn to the needles of a knitting machine, a pair of oscillatory carriers, a yarn guide on each carrier to direct yarn to the rotary members at different points along the same to be measured off thereby at different 100 rates, means on the carriers engaged by the yarn for changing the position of the carriers and yarn guides according to variations in the tension of the yarns, means for turning either of the carriers to and holding it in, idle position with the yarn 105 guide carrier thereby to withdraw its yarn from between the rotary members leaving the other carrier free to oscillate, and spring means for turning the carriers when released by said holding means, to introduce 110 its yarn to the rotary members, substantially as described.
13. In combination, rotary members for furnishing yarn to the needles of a knitting machine, a pair of oscillatory carriers, a yarn guide on each carrier to direct yarn to the rotary members at different points along the same to be measured off thereby at different 115 rates, means on the carriers engaged by the yarn for changing the position of the carriers and yarn guides according to variations in the tension of the yarns, means for turning either of the carriers to and holding it in, idle position with the yarn 120 guide carrier thereby to withdraw its yarn from between the rotary members leaving the other carrier free to oscillate, and spring means for turning the carriers when released by said holding means, to introduce 125 its yarn to the rotary members, substantially as described.
14. In combination, rotary members for furnishing yarn to the needles of a knitting machine, a pair of oscillatory carriers, a yarn guide on each carrier to direct yarn to the rotary members at different points along the same to be measured off thereby at different 130 rates, means on the carriers engaged by the yarn for changing the position of the carriers and yarn guides according to variations in the tension of the yarns, means for turning either of the carriers to and holding it in, idle position with the yarn guide carrier thereby to withdraw its yarn from between the rotary members leaving the other carrier free to oscillate, and spring means for turning the carriers when released by said holding means, to introduce its yarn to the rotary members, said spring

means being common to both carriers and being compressed by the one in idle position and held out of range of the free oscillatory movement of the other carrier, substantially as described.

12. In yarn furnishing means for a knitting machine, the combination of a pair of plain surface conical rolls, means for positively driving one of them and spring means for holding the other roll in contact therewith to be driven frictionally therefrom, said other roll under said spring pressure, being shiftable to different angular positions relative to the drive roll, automatically, according to the position of the yarn at different points along the bite of said rolls, and while maintaining frictional contact with said drive roll to be driven therefrom, and means controlled by the tension of the yarn for shifting said yarn to said different points along the rolls, substantially as described.

13. In yarn furnishing means for a knitting machine, the combination of a pair of plain surface conical rolls, means for positively driving one of them and spring means for holding the other roll in contact therewith to be driven frictionally therefrom, said other roll under said spring pressure, being shiftable to different angular positions relative to the drive roll, automatically, according to the position of the yarn at different points along the bite of said rolls, said spring means exerting its force upon a plate which is turnable about horizontal pivots, and carries a bracket turnable about a vertical pivot on said plate, the bracket carrying the bearings for said shiftable roll, substantially as described.

14. In combination a pair of rotary members for furnishing the yarn at different rates according to the location of the yarn along the bite thereof, with means for driving the same, a yarn guide movable along the same to locate the yarn at points between the said members to be furnished thereby to the needles of a knitting machine, said yarn guide having a range of movement to carry said yarn to a point beyond the said rotary members to idle position, a sweep engaging the yarn at a point thereon between the said members and the needles and connected with the said yarn guide to alter its positions along the rotary members, guide means engaging the said yarn on its way from the rotary members to the needles to provide an extra yarn length between said rotary members and needles, a yarn feed finger with means for automatically moving the same towards and from feeding position, a connection for operating the yarn guide first mentioned upon the operation of the yarn feed finger from one position to the other to shift the yarn to or from idle position in respect to said rotary members, the

said guide means which engages with and provides the extra yarn length being yielding to supply yarn from the said extra length to the needles when the said yarn is shifted from idle position to a position in the bite of the rotary members, substantially as described.

15. In combination, a pair of rotary yarn furnishing members to supply yarn to the needles at varying rates according to the different points along the bite thereof to which the yarn is shifted, a pair of yarn guides each arranged to pass the other for positioning the yarns at different points along said rolls according to the tension of the yarn, means for operating said guides according to the varying tension of the yarns, yarn feed fingers at the needles, means for shifting them automatically to and from yarn feeding position, and connections for shifting the yarn guides to and from an idle position at which yarn furnishing will cease, substantially as described.

16. In yarn furnishing means for knitting machines, the combination of a pair of conical plain surface rolls, means for positively driving one of them, the other being driven by its frictional contact therewith, means for mounting the rolls at one end only, leaving the other ends free, means exerting spring pressure upon the mounting of the friction driven roll, whereby said roll may tip in relation to the other roll, and yarn guide means controlled by the tension of the yarn to shift said yarn along the rolls, yarn fingers to feed the yarn to the needles, said yarn fingers being movable to present and withdraw the yarn relative to the needles, and means for operating the yarn guide means to introduce the yarn to and withdraw the yarn from the rolls in synchronism with the movement of the yarn fingers to and from feeding position, substantially as described.

17. In combination in yarn furnishing means for knitting machines, a pair of plain surface conical rolls, means for driving one of them which in turn drives the other by frictional contact, means for yieldingly mounting the driven roll at one end only to allow it to assume different angular positions relative to the other roll according to the position of the yarn along their meeting line, and guide means for the yarn shiftable along said meeting line according to variations in the tension of the yarn, substantially as described.

18. In combination with a knitting machine, yarn feed fingers, means for automatically operating the said fingers to introduce their yarns to the needles and to withdraw their yarns from the needles, yarn furnishing means comprising rotary members with means for driving them, said rotary members furnishing the yarn at vary-

ing rates according to the position along the said members at which the yarn passes between them, yarn guides, one for each 5
yarn feed finger, shiftable along the rotary members, and having each a range of movement to place its yarn either between the said members for furnishing thereby or in the idle position where it will not be furnished by said members, means connected 10 with said guides and affected by variations in the tension of the yarn for shifting said yarn guides along the yarn furnishing members, to vary the rate of feed according to the tension of the yarn, and an operating connection for each of 15 said guides arranged to work in synchronism with the corresponding yarn feed finger for shifting the guide in respect to said rotary members to introduce its yarn between them simultaneously with the movement of the said corresponding yarn feed finger to feeding position, and for shifting said guide to idle position in respect to said members when the corresponding yarn feed finger is removed 20 from its feeding position relative to the needles, substantially as described.

19. In combination with a knitting ma-

chine having movable yarn feed fingers to introduce the yarns to and withdraw them from the needles, yarn furnishing means comprising rotary members adapted to furnish the yarns at different rates of speed to the needles according to variations in the tension of the yarns, said members having yarn guiding portions to direct the yarn to the bite of the members when moved from idle position, movable yarn guide eyes shiftable along the said members to move the yarn to different positions between them and to and from idle positions, sweeps subjected to the tension of the yarns and connected to the yarn guide eyes for shifting them according to variations in the tension of the yarns, and operating connections to said yarn guide eyes to shift them to idle position and from idle position according as the yarn feed fingers are shifted to introduce the yarn to or withdraw it from the needles and means for operating the yarn feed fingers and said connections, substantially as described.

In testimony whereof I affix my signature.

KENNETH HOWIE.
